FLASHLIGHT

Donald A. Keller, San Dimas, Calif., assignor to Pro-Light Inc., Los Angeles, Calif.

Filed Feb. 23, 1973, Ser. No. 335,342

Term of patent 14 years

Int. Cl. D26—02

U.S. Cl. D48—24 A

FIG. 1 is a front perspective view of a flashlight showing my new design;

FIG. 2 is a side elevational view of the flashlight shown in FIG. 1;

FIG. 3 is a rear elevational view of the flashlight shown in FIG. 1; and

FIG. 4 is a front elevational view thereof.

I claim:

The ornamental design for a flashlight, as shown.
